UNITED STATES PATENT OFFICE

150,379

DESIGN FOR A MAGAZINE BASKET

Edmond J. Spence, New York, N. Y., assignor to Selrite, Inc., New York, N. Y., a corporation of
New York

Application October 25, 1946, Serial No. 134,231

Term of patent 3½ years

(Cl. D33—2)

To all whom it may concern:

Be it known that I, Edmond J. Spence, a citizen of the United States, residing in the city, county, and State of New York, have invented a new, original, and ornamental Design for a Magazine Basket, of which the following is a specification, reference being had to the accompanying drawing, forming part thereof.

The drawing is a perspective view showing the magazine basket.

I claim:

The ornamental design for a magazine basket, substantially as shown.

EDMOND J. SPENCE.
